JACQUARD CYLINDER MOTION

Herbert Victor Foster, Providence, R. I., assignor
to Crompton & Knowles Jacquard & Supply
Company, Pawtucket, R. I., a corporation of
Massachusetts

Application September 25, 1936, Serial No. 102,561

11 Claims. (Cl. 139—329)

This invention relates to improvements in jacquard cylinder motions and it is the general object of the invention to give the cylinder a smoother motion than has been possible with previous constructions, to the end that the cards and their lacings may be subjected to a minimum of wear.

The usual form of jacquard employs a cylinder which is reciprocated in a horizontal direction toward and away from the needle board. A set of cards are employed which are fed one at a time to the needle board by rotation of the cylinder. It has been usual practice to give the cylinder an angular movement sufficient to present a new card during the outward motion of the cylinder away from the needle board, and as a result the cards have been subjected to severe strains. It is an important object of my present invention to provide means for turning the cylinder at a slower more gradual rate than heretofore.

It is a further object of my invention to provide means for giving the cylinder a part of its angular motion during the outward stroke away from the needle board and to complete the angular motion on the return stroke as the cylinder approaches the needles. A still further object is to complete the turning before the cards reach the needle board.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a detailed end elevation of the upper part of a jacquard having my invention applied thereto, the cylinder being shown in the needle indicating position in full lines and partially turned in dotted lines.

Fig. 2 is a view similar to Fig. 1 with the cylinder in its outermost position in full lines and with the angular motion completed, but with the cylinder spaced from the needles in dotted lines.

Fig. 3 is an end elevation taken in the direction of arrow 3, Fig. 1, and

Fig. 4 is a diagrammatic view showing the manner of operating the cylinder.

It is to be understood that the cylinder forms only a part of the jacquard mechanism which is mounted over a loom and only such parts of the jacquard are shown as are necessary to set forth my present invention. Referring to the drawing, particularly Fig. 4, the jacquard frame 10 is provided with a horizontal slide rod 11 connected by a link 12 to an arm 13 moving on a pivot 14.

The arm is rocked in any approved manner so as to move the slide rod in a horizontal direction, giving said rod a reciprocation for each beat of the loom when the jacquard is of the so-called single cylinder type.

My invention relates more particularly to the mechanism for turning the cylinder and by referring to Figs. 1, 2 and 3 it will be seen that the rod 11 has rigidly mounted thereon a bearing 20 for a gudgeon 21 of the four-sided jacquard cylinder 22. There are four lugs 23, 24, 25 and 26 rigid with the cylinder and adapted for engagement with a pawl 30 loosely pivoted on a pin 31 fixed in horizontally adjusted position in a slot 32 formed in a part of the jacquard frame. The pawl has a hook 33 for engagement with the lugs and normally is held by gravity in position for engagement with the upper left lug, as viewed in Fig. 1.

Extending upwardly from the bearing is a stand 35 on which is mounted a stem 36 surrounded by a compression spring 37 which presses down a shoulder 38 on the stem. The lower end of the stem is formed with a head 39 adapted for engagement normally with the upper pair of lugs.

A second frame 40 is mounted to swing pivotally about the gudgeon 21 and has a stem 41 surrounded by compression spring 42 to bear against a shoulder 43. The stem 41 has a bottom or lower head 44 for engagement with the lower pair of lugs. A stop 45 is fixed to the frame 40 and is adapted for engagement with the vertical face 50 of an abutment 51 secured as at 52 to the jacquard frame.

A needle board 60 of the usual form has needles 61 two of which are indicated in Fig. 2 to be responsive to the cards C indicated in dot and dash lines, Fig. 1. The cards are fed progressively by angular motion of the cylinder.

In operation, with the parts in the full line position shown in Fig. 1, the cylinder is in its normal angular position and placed to force a card against the needle board. The head 39 engages the upper lugs 23 and 24 to hold the cylinder with its sides vertical. In this same position the head 44 is held yieldingly against the lower lugs 25 and 26 and acts to hold the frame 40 yieldingly in the full line position of Fig. 1 with the stop 45 spaced from the surface 50.

As the slide rod 11 moves to the left the upper left lug 23 will engage the hook 33 to arrest further movement of the corresponding corner of the cylinder, after which continued outward motion of the cylinder will cause the latter to turn in a right hand direction around the gudgeon 21, and at the end of the outward motion the cyl-

inder will assume the dotted line position shown in Fig. 1. It will be noted that during this motion the cylinder moves away from the needles to a position corresponding approximately to the dotted lines of Fig. 2 before the pawl engages the lug 23, and that during the latter part of the outward motion, stop 45 engages fixed surface 50, causing frame 40 to assume the oblique dotted position of Fig. 1. There is a corresponding up motion of hammer 39 which is induced by the positive action of the pawl and rod 11. At the end of the out motion the head 39 presses down on lug 23, but its turning moment about gudgeon 21 is too small to overcome the effect of head 44 bearing on lugs 24 and 25. The cylinder therefore remains in its partially turned position without completing the full 90° necessary to present the next card.

On the return or inward stroke of the cylinder, head 39 will press down on lug 23 and tend to turn the cylinder in a right hand direction, the turning however being controlled by the engagement of stop 45 with surface 50. Gravity will also assist this turning, since the frame 40 tends to become vertical under gudgeon 21. On this return stroke head 44 will remain in the full line position of Fig. 2 relatively to the cylinder, and the continuing down pressure of head 39 will cause a right hand angular motion of the cylinder until the parts assume the position shown in dotted lines, Fig. 2, with the head 39 in engagement with the two upper lugs and stop 45 ready to leave surface 50. The turning of the cylinder is completed before the next card can reach the needles, after which the cylinder moves to the indicating position, presenting the card to the needles by a right line motion. During this period stop 45 moves away from surface 50, a condition which favors the correct presentation of the cards to the needles.

From the foregoing it will be seen that I have provided means for giving the cylinder two turning impulses one of which occurs when the cylinder is moving away from the needle board the other of which takes place during the first part of the return motion of the cylinder toward the needles and that the effect of this mode of operation is to cause a relatively slow feeding of the jacquard cards so that the latter are subjected to a minimum strain. It will further be seen that the second of the impulses is completed before the card is presented to the needles, a condition which grows out of the fact that the top head is able to return the cylinder to an erect position before the rods 11 have completed their return motion and also because of the fact that the stop 45 is free to move away from the surface 50, thereby permitting the cylinder and two frames to move as a unit in a right line motion. Also, the top hammer head 39 assists in the second turning impulse and serves to maintain the cylinder in correct position after said second impulse is completed. The lower hammer head 44 because of the relation which it sustains to the lugs adjacent thereto prevents the upper hammer from completing the turn which is initiated by the pawl while the cylinder is in its outermost position. To this extent the lower hammer is a yielding check which restrains the normal action of the upper hammer which as used heretofore has been to complete immediately the turning of the cylinder which is started by the pawl. When the parts are in the dotted line position shown in Fig. 1 the upper plunger head acts on the cylinder at a mechanical disadvantage while the lower

head 44 acts through a larger turning moment and is therefore able to restrain the effect of the upper hammer. The latter acts during the return stroke toward the needle board to give the cylinder its second turning impulse but this action is controlled by engagement of the stop 45 with the surface 50.

Having thus described my invention it will be seen that changes and modifications may be made therein by those skilled in the art without departing from the spirit and scope of the invention and I do not wish to be limited to the details herein disclosed, but what I claim is:

1. In a cylinder motion for a jacquard, a needle board having needles, a cylinder, means to move the cylinder away from and toward the needles, means to give the cylinder a primary angular motion in a given direction as the cylinder moves away from the needles, pressure means thereafter tending to give the cylinder a secondary angular motion in said given direction, and a controller for the pressure means to restrain the latter but operative by motion of the cylinder toward the needles to render the pressure means effective to give the cylinder the secondary angular motion in said given direction.

2. In a cylinder motion for a jacquard, a needle board, a cylinder, a member in which the cylinder is rotatable to move said cylinder away from and toward the needle board, a pawl, means to render the pawl operative during motion of the cylinder away from the needle board to give said cylinder an initial turning movement in a given direction, pressure means tending to give the cylinder a second turning movement in said given direction, and control means for the pressure means to render the latter effective to give the cylinder the second turning movement in said given direction as the cylinder moves toward the needle board.

3. In a cylinder motion for a jacquard, a needle board having needles, a cylinder, means to move the cylinder away from and toward the needles, means to give the cylinder a primary angular motion in a given direction as the cylinder moves away from the needles, pressure means thereafter tending to give the cylinder a secondary angular motion in said given direction, and a controller for the pressure means to restrain the latter but operative by motion of the cylinder toward the needles to render the pressure means effective to give the cylinder the secondary angular motion and complete said secondary angular motion in said given direction before the cylinder reaches the needles.

4. In a jacquard cylinder motion, a reciprocating member, a cylinder rotatably mounted with respect to the member, a pawl movable about a fixed axis, means carried by the cylinder to engage the pawl when the member moves in one direction to give the cylinder a first turning impulse, yielding means rendered capable by movement of the cylinder during the first impulse to exert on said cylinder a force tending to give the cylinder a second turning impulse independent of the pawl, restraining means to prevent the yielding means from giving the cylinder its second impulse, and means rendered operative by movement of the member in the opposite direction to lessen the effect of the restraining means in opposing the yielding member, whereby the latter gives the cylinder a gradual second turning impulse when the member moves in the opposite direction.

5. In a jacquard cylinder motion, a needle board, a reciprocating member, a cylinder rotat-

ably mounted on the member and moved by the latter away from and toward the needle board, a pawl effective to give the cylinder an initial turning impulse when the cylinder moves away from the needle board, yielding means rendered operative at the end of the movement of the cylinder away from the needle board tending to give said cylinder a second turning impulse, restraining means to prevent the yielding means from giving the second turning impulse to the cylinder when the latter is remote from the needle board, and means to reduce the restraint exercised on the yielding means as the member moves the cylinder toward the needle board to the end that the yielding means becomes operative to give the cylinder a second turning impulse when moving toward the needle board.

6. In a jacquard cylinder motion, a needle board, a reciprocating member, a cylinder rotatably mounted on the member and moved by the latter away from and toward the needle board, means operative during movement of the cylinder away from the needle board to give said cylinder an initial turning impulse, yielding means tending to give the cylinder a second turning impulse when said cylinder is remote from the needle board, restraining means including a part moving with the cylinder to prevent the yielding means from giving the second impulse to the cylinder, and relieving means rendered operative by movement of the cylinder toward the needle board to progressively reduce the resistance offered thereby to the yielding means to the end that the latter becomes operative to give the cylinder the second turning impulse.

7. In a jacquard cylinder motion, a needle board having needles, a reciprocating member, a cylinder rotatably mounted on the member and moved by the latter away from and toward the needle board, means operative during movement of the cylinder away from the needle board to give said cylinder a turning impulse, pressure means tending to give the cylinder a second turning impulse when said cylinder is remote from the needle board, restraining means including a part moving with the cylinder to prevent the pressure means from giving the second impulse to the cylinder, and relieving means rendered operative by movement of the cylinder toward the needle board to progressively reduce the resistance offered thereby to the pressure means to the end that the latter becomes operative to give the cylinder a completed second turning impulse before the cylinder reaches the needles.

55. 8. In a jacquard cylinder motion, a needle board, a reciprocating rotatable cylinder movable away from and toward the needle board, a frame reciprocating with the cylinder, a second frame pivoted with respect to the cylinder, means operative during motion of the cylinder away from the needle board to give said cylinder an initial turning impulse, a pressure element carried by the first frame and rendered operative at the conclusion of the motion of the cylinder away from the needle board to exert a force tending to give the cylinder a second turning impulse, a

yielding element carried by the pivoted frame and resisting the pressure element, and the pressure means operative through the cylinder to hold the pivoted frame against the stop means, said second yielding element and pivoted frame movable angularly by the pressure means when the cylinder approaches the needle board to the end that the pressure element becomes effective to give the cylinder the second turning impulse as the cylinder approaches the needle board.

9. In a cylinder motion for a jacquard having a needle board, a cylinder, a plurality of lugs fixed with respect to the cylinder, means to move the cylinder and lugs away from and toward the needle board, a pawl to engage one of the lugs as the cylinder moves away from the needle board to give said cylinder an initial turning impulse, pressure means moving with the cylinder to engage one of the lugs and tending to give said cylinder a second turning impulse when the cylinder is remote from the needle board, a frame pivotally mounted with respect to the cylinder, a yielding element carried by the frame to engage two adjacent lugs and resist the action of the pressure means, a stop against which the pressure means holds the frame in an oblique position by a force exerted through the lugs and yielding element, motion of the cylinder toward the needle board rendering the pressure means operative to give the cylinder the second turning impulse and move the frame to an erect position as said frame moves relatively to the stop.

10. In a jacquard cylinder motion, a needle board, a rotatable cylinder, means to move the cylinder away from and toward the needle board, a pawl to cause an initial angular motion of the cylinder as the latter moves away from the needle board, means rendered operative during the latter part of the initial angular motion to tend to give the cylinder a second angular motion, in combination with restraining means including a fixed part and a part movable with the cylinder and effective during motion of the cylinder toward the needle board to retard the action of the second named means and render the latter effective to impart angular motion to the cylinder during a considerable part of the motion thereof toward the needle board.

11. In a jacquard cylinder motion, a needle board, a rotatable cylinder, means to move the cylinder away from and toward the needle board, a pawl to cause an initial angular motion of the cylinder as the latter moves away from the needle board, means rendered operative during the latter part of the initial angular motion to tend to give the cylinder a second angular motion, in combination with restraining means including a fixed part and a part movable with the cylinder and effective during motion of the cylinder toward the needle board to offer a diminishing restraint to the second named means and permit the latter to impart the second angular motion to the cylinder during a considerable portion of the motion thereof toward the needle board.
